UNITED STATES PATENT OFFICE.

FRANK ALLEN, OF WORCESTER, MASSACHUSETTS, ASSIGNOR TO HORNER BROTHERS, OF PHILADELPHIA, PENNSYLVANIA.

DESIGN FOR A CARPET.

SPECIFICATION forming part of Design No. 13,100, dated August 1, 1882.

Application filed July 5, 1882. Term of patent 3½ years.

To all whom it may concern:

Be it known that I, FRANK ALLEN, of the city of Worcester, in the county of Worcester and State of Massachusetts, have invented and produced a new and original Design for Carpets, of which the following is a specification.

The nature of my design is fully represented in the accompanying photographic illustration, to which reference is made.

I claim as my invention—

The design for a carpet, as shown.

Witnesses: FRANK ALLEN.

S. R. BARTON,

CHAS. H. BURLEIGH.
